UNITED STATES PATENT OFFICE.

EDWARD G. HEARTICK, OF LOUISVILLE, KENTUCKY.

REGISTER WALL GUARD.

Application filed January 9, 1922. Serial No. 527,859.

To all whom it may concern:

Be it known that EDWARD G. HEARTICK, citizen of the United States of America, residing at Louisville, in the county of Jefferson, State of Kentucky, has invented certain new and useful Improvements in Register Wall Guards, of which the following is a specification.

This invention relates to heating and ventilating and especially to hot air heating wherein floor registers are employed.

More particularly the invention relates to a hood or guard for floor registers.

One important object of the invention is to provide an improved, simple and cheap hood or guard for floor registers.

A second important object of the invention is to provide an improved floor register hood which will be of extremely light construction so that a person coming into collision with the guard will not trip but will simply kick the guard before him.

A third important object of the invention is to provide an improved light and efficient guard which, when applied to a floor register located near a wall will deflect the hot air rising through the register away from the wall and thus prevent discoloration of the wall.

A fourth important object of the invention is to provide a floor register guard which is of such improved construction that baffles of cheese cloth or other like material may be employed for the purpose of preventing dust from entering the room from the register.

A fifth important object of the invention is to provide a floor register guard having an improved arrangement of baffles which may be moistened with a suitable medicament for causing the air of a room to have antiseptic or curative properties or which may similarly be perfumed for giving an agreeable scent to the air.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:

Figure 1 is a view of the blank from which the preferred form of the invention is made.

Figure 2 is a front elevation of the preferred form.

Figure 3 is an end elevation thereof showing the manner of holding the baffles in place.

Figure 4 is a cross section of the preferred form showing one arrangement of baffles.

Figure 5 is a view similar to Figure 4 but showing a second form or arrangement of baffle.

In the embodiment of the invention as herein illustrated the preferred form is disclosed in Figures 1 to 5 inclusive and in this form a blank of thin sheet metal is employed to form the body and sides of the hood. This blank consists of a rectangular center portion 10 at each end of which is a multiplicity of strips 11 each defined from the body by a fold line 12 and separated from the adjacent strips by slits 13. The free ends of these strips are preferably rounded as at 14 and in each free end is punched or otherwise formed a hole 15. These strips 11 are all of the same length at both ends. Along the edges of the body and the outermost strips are edge folds 16 defined by the fold lines 17.

In forming the device from this blank the edge folds are doubled to form the beads 18 shown in Figures 3, 4, and 5. After this the stripes 11 are bent at right angles to the body and the latter curved transversely until the holes or openings 15 are brought into registration so that a fan stick structure is formed at each side of said body. The reduced ends of a cross rod 19 are then passed through the respective sets of holes and nuts 20 screwed thereon. This completes the device in its plain form without baffles and it may be used in this form by placing it over a floor register with the body curved away from the adjacent wall so that the hot air rising from the register will be directed by the curvature of the hood in a substantially horizontal direction away from said wall.

In Figure 4 one arrangement of baffles is shown in which a plurality of narrow strips 21 are employed. These strips, in common with any of the other baffles used, may be made of any desired fabric such as loosely woven cotton goods (cheese cloth is found very suitable) or any other material adaptable for the purpose. In this form the baffles are arranged in staggered relation. In the form in Figure 5 a single baffle 22 is

employed which is made of a porous fabric and extends practically across the entire hood so that the incoming air is filtered through the fabric while the other form traps the dust by the dust laden air striking against the baffles and sticking thereto.

These baffles are applied by wedging adjacent end strips 11 apart and tucking the ends of the baffles between them, a pin being inserted to prevent accidental withdrawal as shown in Figure 3. It is obvious that other arrangements of baffles may be used as desired.

It is to be noted that the material of which the hood is made is very light so that the hood is so light that, if struck by the foot, it will be pushed out of the way and not trip the person striking it.

There has thus been provided a simple and efficient device of the kind described and for the purposes specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. In a device of the kind described, a hood formed of a single piece of sheet metal having its central portion bent to arcuate shape and its ends slit and bent at right angles to the body to provide strips having their free ends overlapping, and means to hold said free ends in overlapping relation and the free ends on one side in fixedly spaced relation to the free ends on the other side.

2. In a device of the kind described, a

hood formed of a single piece of sheet metal having its central portion bent to arcuate shape and its ends slit and bent at right angles to the body to provide strips having their free ends overlapping, means to hold said free ends in overlapping relation and the free ends on one side in fixedly spaced relation to the free ends on the other side, and a baffle arranged across the hood and having its ends secured between adjacent end strips.

3. In a device of the kind described, a hood formed of a single piece of sheet metal having its central portion bent to arcuate shape and its ends slit and bent at right angles to the body to provide strips overlapping at their free ends, and a rod connecting the strips at one end with the strips at the other.

4. In a device of the kind described, a hood formed of a single piece of sheet metal having its central portion bent to arcuate shape and its ends slit and bent at right angles to the body to provide strips overlapping at their free ends, a rod connecting the strips, and a baffle arranged across the hood and having its ends secured between adjacent end strips.

5. In a device of the kind described, a hood formed of a single piece of sheet metal having its central portion bent to arcuate shape and its ends slit and bent at right angles to the body to provide strips overlapping at their free ends, a rod connecting the strips at one end with the strips at the other, a baffle consisting of a fabric strip having its ends tucked between adjacent end strips at opposite sides of the body, and pins extending through the outwardly projecting end portions of the baffle.

In testimony whereof I affix my signature.
EDWARD G. HEARTICK.
